UNITED STATES PATENT OFFICE

94,892

DESIGN FOR A WASHING MACHINE

Lurelle Guild, Noroton, Conn., assignor to General Electric Company, a corporation of New York

Application December 13, 1934, Serial No. 54,413

Term of patent 14 years

To all whom it may concern:

Be it known that I, Lurelle Guild, a citizen of the United States, residing at Noroton, county of Fairfield, State of Connecticut, have invented a new, original, and ornamental Design for a Washing Machine, of which the following is a specification, reference being had to the accompanying drawing, forming a part thereof.

The figure is a perspective view of a washing machine showing my new design.

I claim:

The ornamental design for a washing machine substantially as shown.

In witness whereof, I have hereunto set my hand this 7th day of December, 1934.

LURELLE GUILD.
